UNITED STATES PATENT OFFICE.

JOHN M. HANSEN, OF PITTSBURGH, PENNSYLVANIA, ASSIGNOR TO FORGED STEEL WHEEL COMPANY, OF PITTSBURGH, PENNSYLVANIA, A CORPORATION OF PENNSYLVANIA.

HYDRAULIC PRESS.

1,191,302.

Specification of Letters Patent. Patented July 18, 1916.

Application filed June 23, 1913. Serial No. 775,344.

To all whom it may concern:

Be it known that I, JOHN M. HANSEN, a citizen of the United States, and resident of Pittsburgh, in the county of Allegheny 5 and State of Pennsylvania, have invented a new and useful Improvement in Hydraulic Presses; and I do hereby declare the following to be a full, clear, and exact description thereof.

10 My invention relates to hydraulic presses and to that type of presses generally used for extremely heavy forging operations. These presses are often built to exert power of 10,000 tons or more and the main parts of 15 the press are very large and heavy, some of them being as heavy as one hundred tons, indeed being only limited in size and weight by the capacity of railroads to transport the same. The presses as made are formed of 20 platens connected by strong forged steel columns resting on suitable foundations, the main parts being the bottom platen or anvil, the top platen carrying the hydraulic cylinder and a moving platen operated by the 25 hydraulic piston. The columns for these presses are made as large as two feet in diameter.

As heretofore constructed the hydraulic cylinder has formed a part of the cap piece 30 or top platen and the tremendous strain brought upon the cylinder and cap piece has led to the development of cracks in the cylinder. As the cylinder was formed integral with the cap piece, the strain was thrown 35 upward within the casting as a tension strain against the upper part thereof, and as the cylinder was mainly located in the lower or compression portion of the casting, the tension strain was so great that it was liable to 40 cause vibration in the body of the casting and this would lead to contraction at the base of the cylinder itself where it projected down from the cap piece. This in time was liable to develop cracks within the body 45 of the casting usually within the cylinder, even though these parts were formed of the strongest cast steel. The tremendous strain also caused a deflection in the body of the casting which caused a diagonal thrust upon 50 the forged steel columns and the nuts thereon above the cap piece which strain stripped the threads of the columns on the inner sides thereof, making it necessary to replace the columns. Such accidents led to 55 great loss and delay in the cost of replacing

the injured parts including the dismantling and rebuilding of the tremendous machine, and the loss of the productive work of the press during the delay.

The object of my invention is to provide 60 a hydraulic press, the cap piece of which is sufficiently strong to be entirely without deflection under such tremendous strain, and in which that strain is brought directly upon the columns in such way as to relieve the 65 same from such diagonal strains leading to the stripping of the threads, etc.

It consists, generally stated, in the combination with the anvil block or lower platen and the connecting columns, of a hydraulic 70 cylinder, and the cap piece connected to the columns, and separate from and sustaining the hydraulic cylinder, said cap piece being of sufficient thickness or depth to sustain the strain without deflection of its body, and so 75 transmitting the strain on direct vertical lines to the columns.

It also comprises the employment with 80 said separate cylinder and cap piece of a cross head supported by the columns engaging the lower portion of the cylinder to sustain it against outward strain. It also consists in other improvements as hereafter described.

In the accompanying drawings Figure 1 85 is a vertical section of the press on line 1—1 Fig. 3; Fig. 2 is a vertical section of the upper part of the press on the line 2—2 Fig. 3; Fig. 3 is a top or plan view of the cap; Fig. 4 is a vertical section of the upper portion of the cap on line 4—4 Fig. 3; Figs. 5 and 6 are perspective views of the cap piece; and Fig. 7 is a like view of the cylinder.

The anvil block or lower platen 2 is supported on any suitable foundation, and the 95 columns 3 pass through the anvil block and extend upwardly through the cap piece 4, these parts being bound together by the nuts 5 below the anvil piece 2 and the nuts 6 above the cap-piece, said nuts, as illustrated, being of the split type clamped in place by the bolts 7 after the main parts are thus rigidly bolted together. Secured upon the columns 3 in any suitable way are the collars 8 on which rests the cross head 9. Held between the cap piece 4 and the cross head 9 is the hydraulic cylinder 10 which fits against the lower face of the cap piece 4 and is seated therein, such as in the shallow cup shaped recess 11, while its lower edge is 100 105 110

formed with a rabbet 12, providing a vertical cylindrical face 13 fitting within the inner cylindrical face 14 of the cross head, and a shoulder 15 resting upon a shoulder 16 of the cross head, the cylinder being thus supported and held rigidly between the cap piece 4 and cross head 9.

The cap piece 4 is formed as a separate casting from the cylinder and is made of sufficient thickness or depth and strength to sustain without possible deflection all strains brought upon it under the tremendous hydraulic power developed in the press. For example, in the press as illustrated the cap piece is between 6 and 7 feet in thickness and fits for this length around the columns 3. I thus provide a separate cap piece of such thickness and with a continuously extending body portion in the lower part thereof to sustain all upward strain not only by the upper or tension portion thereof, but by its lower or compression part, so that vibration in the body of the casting will not be developed even under the tremendous strain produced. The cap piece is so thick and rigid that no deflection can occur in the body thereof, and consequently as the nuts 6 contact directly with the upper surface thereof against the bearing faces 17 thereof, the upward strain is transmitted on direct lines to the nuts 6 parallel with said columns. The cup-shaped seat 11 is shallow and corresponds exactly in shape to the closed or bottom portion of the cylinder 10 which fits into the same for about the thickness of the bottom of the cylinder, thus centering it and forming in effect a continuous solid body of metal from the inner wall of the cylinder to the top of the cap piece. The cup shaped seat is located only within the compression portion of the cap piece, so that the direct strain is limited to such compression portion thereof. The cap piece may, however, be cored at 36 in such way as will not reduce its rigidity. Thus the cast steel cylinder, the walls of which are made, say, a foot and a quarter in thickness, is supported and firmly held between the cross head 9 and the cap piece 4, and is securely held against all strains brought upon it even under the tremendous force exerted. For example, the upward strain is sustained by the cap piece, which is of so great thickness and strength as to prevent deflection. The strain is also transmitted directly to the nuts on direct vertical lines and on lines parallel to the columns themselves with which the cap piece engages for such length as to make deflection either in the columns or on the cap piece impossible. In like manner the bursting strains developed within the cylinder are sustained by the cross head itself engaging with the lower end thereof, which in turn is supported by the heavy columns of the press. Thus all vi-

bration which might lead to development of cracks within the cylinder is absolutely prevented; first by removing if possible all inward strains in the body of the cap piece which might be present where the cylinder and cap piece were integral, second by transferring the direct strain within the cylinder from the tension portion of the casting down to the lower or compression portion of the separate cap piece; third by making said cap of sufficient thickness to prevent the development of stress or strain within the same, or permit any deflection within the body, this also overcoming all possibility of diagonal strain upon the supporting columns or their nuts; and again by sustaining the base of the cylinder firmly against outward bursting strains.

The drawings also illustrate the usual parts in a hydraulic press of this character, for example, one for the forging of car wheels in which the main piston is shown at 20 being carried by the moving platen 21 traveling on the columns 3, said platen being raised by the rams 22 supported on the cap piece 4 and fitting into the seats 23 thereof, the plungers 24 of said rams being connected to the cross head 25 having rods 26 extending down to and engaging with the lugs 27 of the moving platen. Said platen carries the die 28 which co-operates with the anvil die 29 in the main forging operation. The main piston 20 is formed hollow, so forming a cylinder 30 to receive the piston 31 operating the mandrel 32. The anvil also supports a cylinder 33 operating a plunger 34 and through it the ram 35. These parts are, of course, changed as desired according to the work to be performed.

What I claim is:

1. In a hydraulic press, the combination of an anvil block, a cap piece and columns connecting the same, and a separate hydraulic cylinder, the cap piece being of sufficient thickness to sustain the pressing strain brought upon it without deflection of its body, and having a recess in its lower face wholly located within the compression portion of the cap piece, and the cylinder being seated in said recess.
2. In a hydraulic press, the combination of an anvil block, a cap piece, and columns connecting the same, said cap piece having a recess in its lower face, the bottom of said recess being horizontal and exerting a direct bearing on said cylinder, a separate hydraulic cylinder fitting in said recess, and a cross head supported on said columns and extending around the open base of the hydraulic cylinder, said cap-piece being of sufficient thickness to sustain the strains brought on it without deflection of its body.
3. In a hydraulic press, the combination of an anvil block, a cap piece having a shallow recess having a flat bottom in its lower

face, a cylinder having a flat upper face fitting in said recess, and a cross head connected to the columns and engaging with the lower open end of the cylinder, said cap 5 piece being of sufficient strength to sustain the strains brought on it without deflection of its body.

4. In a hydraulic cylinder, the combination of an anvil block, a cap piece and 10 columns connecting the same, a separate hydraulic cylinder, and a cross head supported on said columns, the cap piece being of suffi-

cient thickness to sustain the pressing strain without deflection of its body and having a recess wholly in the compression portion 15 thereof, the cylinder being seated within said recess, and the cross head surrounding the base of the cylinder.

In testimony whereof, I the said JOHN M. HANSEN have hereunto set my hand.

JOHN M. HANSEN.
